UNITED STATES PATENT OFFICE.

WALLACE C. HILL, OF UTICA, NEW YORK.

WINDING MECHANISM FOR MUSICAL INSTRUMENTS.

1,145,836.

Specification of Letters Patent.

Patented July 6, 1915.

Application filed February 5, 1915. Serial No. 6,360.

To all whom it may concern:

Be it known that I, WALLACE C. HILL, a citizen of the United States, residing at Utica, in the county of Oneida and State of New York, have invented certain new and useful Improvements in Winding Mechanism for Musical Instruments, of which the following is a specification, reference being had therein to the accompanying drawing.

10 My invention relates to a winding mechanism for musical instruments, and I declare the following to be a full, clear, concise and exact description thereof sufficient to enable anyone skilled in the art to which it appertains to make and use the same, reference being had to the accompanying drawings in which like reference characters refer to like parts throughout the specification.

20 The object of the invention is to provide an efficient, simple mechanism adapted for winding up the motor spring of a phonograph or music box by the use of a lever actuated in a horizontal plane in contradistinction to the turning of a crank, as has been 25 employed heretofore. The actuation of a lever in a horizontal plane, whereby to wind up the main spring is much easier than the old manner of winding or turning a crank. This object is disclosed in the drawings in 30 which,

Figure 1 is a perspective view of a musical cabinet, containing the improved winding mechanism; Fig. 2 is a side elevation of a member and pawls employed, the same 35 being greatly enlarged; Fig. 3 is an enlarged perspective view of the parts seen in Fig. 2; Fig. 4 is an enlarged detail view of a member used to secure a sleeve to the member shown in Fig. 2; Fig. 5 is an enlarged view 40 of the winding mechanism, showing a vertical section of the upper portion of the music cabinet; Fig. 6 is an enlarged view of the winding mechanism, showing a certain 45 modification, the upper portion of the cabinet being in section; Fig. 7 is a plan view of the winding mechanism, looking down from above.

Referring more particularly to the drawings, a cabinet or music box is represented 50 by —1—, the same having a top 2, hinged in the usual manner, so that it can be thrown back by the handle 3. The cabinet has also

the front door 4, which is hinged to the walls of the cabinet —1— in the well known manner. Near the upper portion of the 55 cabinet —1—, in the wall thereof, is a long narrow slot 5, adapted for the projection of the handle 6, provided with an angular portion 7, secured to the member 8 having the horizontal parts 9—9 from which arise 60 the studs or members 10—10. To the studs 10, are pivotally mounted the dogs or pawls 11—11, adapted to alternately engage or fall by gravity into the open spaces 40 between the links 41 of the endless sprocket chain 12, 65 which runs over the sprocket wheels 13 and 14. The sprocket wheel 13 is loosely mounted upon a shaft 15 having bearings in the standards 16—16. The sprocket wheel 14 is mounted upon the shaft 60 having bearings 70 in the standards 17—17 and is in mesh with the smaller gear wheel or pinion 18. The pinion 18 is keyed or otherwise secured to the shaft 19, so as to turn therewith. The shaft 19 is supported in the bearing in the 75 standard 20 and has attached in a rigid manner to its opposite end a spur gear 21 in mesh with the spur gear 22 keyed to the shaft 23, so as to turn therewith. The shaft 23 is adapted for the securing of one end of 80 the main spring 24. The other end of the main spring 24 is fastened to the casing 25, mounted within the upper portion of the cabinet —1—. The shaft 23 is held in the 85 bearings of the standards 26—26 and has fixed to its opposite end a spur gear 27 adapted for rotating the other gears that are employed for turning the disk or cylinder of the phonograph or musical instrument, in the well known manner of the art.

90 A member 28 having a curved end 29 and a threaded end 30 is projected through a suitable recess in the member 8 and in the adjacent portion 7 of the handle 6, whereby the curved end 29 may securely hold a sleeve 31, which is adapted to slide along the bar 32 embedded at either end in the walls of the cabinet —1—. The member 28 is held in assembled position by the nut 33.

95 A coiled spring 34 is fastened at one end 100 to the wall of the cabinet —1— and at its other end to the member 8, which is provided with the aperture 35 for the purpose, so that when the handle 6 is manually pulled

and released in the direction indicated by the arrow 36 in Fig. 5, the spring 34 will automatically return the handle 6 to its original position as illustrated in Figs. 1 and 5.

5 The operation of the device is effected by manually pulling on the handle 6, which is formed at an angle of about sixty degrees to its horizontal portion 45, whereby to aid in giving a better leverage. As the handle 10 6 is pulled in the direction indicated by the arrow 36 in Fig. 5, the free end of the lower pawl 11 will automatically drop by its own gravity into the open space 40 adjacent of the chain 12 and thereby force the chain 12 15 in the direction indicated by the arrows in Figs. 5 and 6. Simultaneously with the engagement of the lower pawl 11 in the open space 40 of the chain 12, the upper pawl 11 will ride freely over the links of the chain 20 12, as illustrated in dotted lines in Fig. 5, until the handle 6 has reached the limit of its forward movement, which limit is adjacent the periphery of the sprocket wheel 14. Immediately the manual pull upon the 25 handle 6 is released, the same will return to its original position because of the tension of the coiled spring 34. As the handle 6 begins to return, the free end of the upper pawl 11, will automatically drop by gravity 30 into the open space 40 adjacent to the chain 12 and thereby continue to actuate the chain 12; without any interruption, in the direction heretofore mentioned as indicated by the arrows in Fig. 5. In this latter movement, the lower pawl 11 will ride freely 35 over the links of the chain 12. The actuation of the chain 12 causes the sprocket wheel 14 to revolve and thereby turn the pinion 18, which in turn causes the shaft 19, the gear 21, the gear 22, and the shaft 23 to revolve, whereby the main spring 24 is wound up to run the disk or cylinder 40 parts of the phonograph or musical instrument. The horizontal reciprocal movement 45 of the handle 6 is guided by the bar 32 to which it is intermediately connected by the sleeve 31 and the member 28. The member 28 is adapted to permit a limited amount 50 of movement of the handle 6 in relation to the sleeve 31, whereby the sleeve 31 will not bind upon the bar 32, when the handle 6 is being manipulated.

Fig. 6 illustrates a certain modification in that a handle 50, fixed to the end of a bar 51, projecting in a sliding manner, through an aperture in the wall of the cabinet —1— is employed to draw the member 28 against the tension of the spring 34. The bar 51 is formed with a long narrow recess 52, which loosely receives a headed bolt 53, secured to the member 28. Obviously by pulling and releasing the handle 50, the chain 12 will be actuated as heretofore described. The recess 52 permits the bar 51 to be pushed

back into the cabinet —1—, when the main 65 spring 24 has been wound to its maximum limit and the member 28 having the pawls 11 is adjacent the near side of the cabinet —1—.

The engagement of the pawls 11 with the 70 chain 12, subject only to the tension of the coiled spring 34, controls the movement of the said chain 12, so that the main spring 24 will be held in wound condition to any 75 desired degree, as determined by the extent of the reciprocation of the handle 6, when the hand of the operator is withdrawn from the handle 6.

Having thus described my invention what I claim as new and desire to secure by Letters Patent is:

1. In a winding mechanism for musical instruments, a spring, an endless chain for winding said spring, means connecting said spring with said endless chain, a handle, 85 whereby said chain may be actuated in a given direction, and means for automatically continuing said actuation.

2. In a winding mechanism for musical instruments, a spring, an endless chain running over sprocket wheels for winding said spring, means connecting said spring with said endless chain, a member having pawls for moving said chain, a handle for moving said member having pawls in one direction, 95 and a spring for moving said member having pawls in the reverse direction.

3. In a winding mechanism for musical instruments, a main spring, an endless chain, means connecting said spring with said endless chain, sprocket wheels over which said chain runs, one of said sprocket wheels in mesh with a smaller sprocket wheel adapted for winding said main spring of a musical instrument, a member having pawls adapted 100 to engage said chain, a handle for moving said member having pawls in one direction, and a spring for moving said member having pawls in the reverse direction, whereby said chain is moved to wind said spring for 105 running a musical instrument.

4. In a winding mechanism for musical instruments, a main spring, an endless chain, means connecting said main spring with said endless chain, a lever actuated in a horizontal plane for moving said endless chain, whereby to wind up said main spring, and a spring for pulling said lever in one direction.

5. In a winding mechanism for musical instruments, a main spring, a shaft for securing one end of said main spring, an endless chain, means connecting said endless chain with said shaft, and means for moving said endless chain to revolve said shaft, 120 whereby to wind said main spring.

6. In a winding mechanism for musical instruments, a main spring, a shaft upon

which one end of said main spring is attached, a spur gear attached to said shaft, an endless chain running over sprocket wheels, means connecting said spur gear 5 with one of said sprocket wheels, and means for moving said endless chain to revolve said shaft, whereby to wind said main spring.

In testimony whereof I have affixed my signature in the presence of two witnesses.

WALLACE C. HILL.
